(57) CLAIM

The ornamental design for a music stand, as shown and described.

DESCRIPTION

FIG. 1 is a perspective view of the front, top and right side of a music stand showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line showing of the music stand is included for the purpose of illustrating portions of the music stand and forms no part of the claimed design.
